UNITED STATES PATENT OFFICE.

PATRICK TRESTON DUNLOP, OF SPRINGFIELD, MISSOURI, AND HENRY W. JACOBS, OF TOPEKA, KANSAS.

FOUNDATION-RING FOR STEAM-BOILERS.

1,197,806.

Specification of Letters Patent.

Patented Sept. 12, 1916.

Application filed May 17, 1915. Serial No. 28,520.

To all whom it may concern:

Be it known that we, PATRICK T. DUNLOP and HENRY W. JACOBS, citizens of the United States, and residing at Springfield, 5 in the county of Greene and State of Missouri, and at Topeka, in the county of Shawnee and State of Kansas, respectively, have invented certain new and useful Improvements in Foundation-Rings for Steam-Boilers, of which the following is a description, reference being had to the accompanying drawings, which form a part of our specification.

Our invention relates to foundation rings 15 more especially adapted for use in connection with the open type or locomotive boilers which are provided with upwardly presented water-tubes whereby circulation between the lower and upper part of the fire-box of the 20 boiler may be had.

The object of our invention is to provide a foundation ring for a boiler of the class specified, which will provide water-circulating chambers in the foundation rings arranged to have communication not only with the water-tubes of the fire-box, but also with the water-legs which are provided intermediate of the flue-sheet and throat-sheet and intermediate of the door-sheet and back-head of the fire-box of the boiler.

A further object of our invention is to provide a foundation ring wherein the sections or portions, provided with the water-chambers, may be made of comparatively light material such as steel plate, adapted to be rolled or otherwise shaped into proper form, thus providing a foundation ring which will be inexpensive to manufacture. The transversely extending sections or portions of our improved foundation ring are 35 preferably made solid, so that these portions or sections may be made of cast steel.

In the preferable construction of our invention, the solid or transversely extending sections of the foundation ring are provided with ports or openings at points where they are connected with the hollow longitudinal sections of the foundation ring, so as to enable circulation between the hollow or chambered portions of the foundation ring and the front and back water-legs of the boiler.

As is apparent from the foregoing statements, the invention provides a foundation ring made in sections, the various sections, 55 however, being arranged to be rigidly or

permanently secured together in any suitable manner, as, for example, by welding the sections together so as to form a proper water-tight construction, as will be fully understood from the following detailed description of the drawings wherein:—

Figure 1 is a perspective view of one form of our improved foundation ring, partially shown in section, with an end of one of the longitudinally disposed sections being shown unattached to the transversely extending section. Fig. 2 is a vertical cross-section of a hollow longitudinal section illustrating one form of our invention, composed of a top or inverted U-shape channel section to which a flat bottom is welded. Fig. 3 is a vertical sectional view of a modified form of hollow longitudinal section of the foundation ring, wherein the bottom is arranged slightly above the lower edges of the side walls. Fig. 4 is a vertical cross-section of another modified form of longitudinal section of a foundation ring; the longitudinal section being shown composed of two inverted channel sections permanently secured together. Fig. 5 is a vertical sectional view of still another modified form of hollow longitudinal section or portion of a foundation ring, composed of two pieces or members secured together in any suitable manner such as by rivets and the like, so as to provide a rigid construction. Fig. 6 is a vertical cross-section of a further modification of the longitudinal section of a foundation ring, wherein the bottom or lower part of the longitudinal section is welded to the side wall thereof.

Our invention contemplates making a foundation ring in sections, that is, with the longitudinally disposed portions of the foundation ring made separate from the transversely disposed portions or sections of the foundation ring; the transversely disposed portions of the foundation ring being preferably made of cast steel, or other suitable metal, and, therefore, made solid throughout except at points where the transversely disposed sections are united to the longitudinally disposed sections of the foundation ring, at which points we prefer to provide ports for the purpose hereinafter specified.

The transversely disposed section or end 10 of the foundation ring is preferably provided with a depending portion 11 to consti- 110

tute an anchor for the expansion pad usually arranged between the back-head and the engine-frame, while the section or end 10^a is provided with a similar depending portion 12 adapted to constitute a suitable anchor or stay between the throat-sheet and the engine-frame. The transversely disposed sections or portions 10 and 10^a are preferably provided with angularly disposed ends, as clearly shown in Fig. 1; and these ends are preferably cored so as to provide ports 13 adapted to communicate with the chambers with which the longitudinally disposed portions of the foundation ring are provided, as hereinafter set forth; the outer end of port 13 being disposed upwardly so as to afford communication with the front and rear water-legs of the fire-box. At points coincident with the ports 13 in the transversely disposed sections, the sections 10 and 10^a are provided with upwardly presented flanges or portions 14 which may be provided with holes to permit the door-sheet and flue-sheet to be riveted thereto in the usual manner.

The side or longitudinally disposed sections of the foundation ring, as illustrated in Figs. 2, 3 and 6, are made of two parts or members, one forming the top and two side walls, while the other forms the bottom; the two parts or members are preferably welded together in the different manners illustrated in the respective figures, so as to constitute an integral structure; the bottom portion 15 in Fig. 2 being welded to the extreme lower edges of the side walls 16, 16, so as to be flush therewith; while in the construction illustrated in Fig. 3 the bottom 15^a is preferably secured slightly above the lower edges of the side walls 16^a as shown, thus providing a longitudinal section which is not quite as deep vertically as the section disclosed in Fig. 2.

In Fig. 6, we show a longitudinal section having outwardly bowed or curved side walls 16^b and the bottom portion 15^b is inserted within the longitudinal section and welded on top of the inwardly presented lower edges of the side walls.

In the construction shown in Figs. 2, 3 and 6, the side walls and bottom, as above stated, are welded together, thereby forming an integral structure.

In Fig. 4, we show the longitudinal section of a foundation ring composed of two parts, each made or rolled into channel form; the one part or channel constituting the top and two side walls, while the other channel or member constitutes the bottom 60 of the longitudinal section of the foundation ring. The bottom channel, like the main portion or channel, is inverted so that the sides or flanges of both channels extend downwardly; the bottom channel or member 65 being so constructed as to permit it to be

forced or inserted within the side walls of the longitudinal section, to permit the flanges of the bottom channel or member 15^c to lie flush or extend parallel with the sides 16^c of the main channel or body portion of the longitudinal section. With this construction, wherein considerable overlapping portions are provided, the two members or channels may be secured together by riveting the flanges of the bottom 15^c to the side walls 16^c, as clearly shown at 17; the comparatively wide surface or area of abutting metal enabling a suitable water or fluid-tight connection being obtained by the method shown and a permanent or rigid connection between the portions provided.

In Fig. 5, we present another modified form of longitudinal section, employing the method shown in Fig. 4, of securing the parts together. The main or body portion of the longitudinal section is composed of a single piece constituting the top and two side walls, the latter being bowed or bent so as to present an ogee curve or S-shape in cross-section, with the lower ends of the side walls presented outwardly. In this construction or form, the bottom 15^d is made of a flat piece or sheet and of a width to permit it to extend from tip to tip of the lower ends of the side walls 16^d, thus providing a comparatively large area of overlapping or abutting surface between the lower ends of the side walls 16^d and the bottom member or piece 15^d, which permits the two members or portions to be riveted together, by means of a suitable number of rivets as indicated at 17^d, producing, like in the construction shown in Fig. 4, a permanent or rigid connection between the portions.

The upper surfaces of the longitudinal sections are provided with suitable openings to receive the ends of water-tubes; the openings being indicated at 18 in Fig. 2; at 18^a in the construction illustrated in Fig. 3; at 18^b in the construction illustrated in Fig. 4; at 18^c in the construction shown in Fig. 5; and at 18^d in the construction illustrated in Fig. 6.

With the longitudinal sections constructed, as illustrated, namely with the bottom portions permanently secured to the side walls of the longitudinal sections, it becomes necessary to provide the bottoms with suitable openings which are adapted to register or rather are formed in alinement with the openings in the top surfaces, as shown at 19 in Fig. 2; at 19^a in Fig. 3; at 19^b in Fig. 4; at 19^c in Fig. 5; and at 19^d in Fig. 6. These openings in the lower or bottom walls 125 of the longitudinal sections are preferably threaded, as shown in the drawings, so as to permit threaded plugs or members of, suitable form, to be secured therein.

The ends of the longitudinal sections are 130

intended to be welded to the transverse sections, and this is accomplished by preferably beveling or forming the abutting ends in the diagonal manner shown, so as to provide 5 as great a surface for welding as possible, and thus obviate the possibility of a transverse fracture at the juncture of the transverse and longitudinal sections.

A foundation ring, constructed as herein 10 described, enables the use of light material, such as rolled steel having greater density and closeness of grain than would be the case if cast metal were employed for the hollow longitudinal or fluid circulating sections, and, therefore, provides a lighter 15 foundation ring, which, however, possesses the requisite strength.

The longitudinal sections may be given 20 any desired shape or suitable cross-sectional contour, which will permit the bottoms of such sections to be properly and permanently secured to the side walls; and while we have illustrated several forms, it is evident that certain other modifications may be 25 made without, however, departing from the spirit of our invention.

What we claim is:—

1. A foundation ring for steam boilers, composed of solid transverse sections of 30 cast metal and hollow longitudinal sections of sheet metal of greater density and comparative lightness, the respective sections being welded together and the transverse sections provided with angularly disposed ends 35 having upwardly and laterally disposed ports adapted to communicate with the chambers of the longitudinal sections and

with the water-legs of the firebox, while the longitudinal sections have their top, side and bottom walls rigidly secured together 40 with the top and bottom walls provided with alined openings.

2. A foundation ring for steam boilers, composed of solid cast steel transverse portions having depending anchor-portions 45 and angularly disposed ends provided with upwardly and laterally disposed ports, and longitudinal portions of channeled sheet metal sections of greater density secured together, the upper surfaces of the longitudinal portions being provided with water-tube receiving openings while the bottom surfaces thereof are provided with alined threaded openings, the transverse portions and longitudinal portions being welded to 50 55 together.

3. A foundation ring for steam boilers, composed of solid transverse sections of cast metal and hollow longitudinal sections of sheet metal of greater density and comparative lightness, the respective sections being welded together and the transverse sections provided with angularly disposed ends having upwardly and laterally disposed ports and upwardly presented attaching 60 65 flanges about said ports, while the longitudinal sections have their tops, sides and bottom walls rigidly secured together.
